REFUSE PIT

Application filed February 11, 1927. Serial No. 167,545.

My invention relates to combustion apparatus and more particularly to apparatus of this character which are provided with pits for the reception of refuse, and it has for an object the provision of apparatus for minimizing the premature discharge of combustible material from these refuse pits.

More specifically the object of my invention is to provide shield means beneath the grinder rolls commonly associated with the refuse pit and effective to impede the sifting of fine material from the refuse pit and to insure its removal therefrom only by direct action of the grinder rolls.

Apparatus embodying features of my invention is illustrated in the accompanying drawings forming a part of this specification wherein:

Fig. 1 is a fragmentary longitudinal section through a stoker showing one form of my invention as applied to a clinker pit having a single clinker grinder roll;

Fig. 2 is a view similar to Fig. 1 showing one form of my invention applied to a clinker pit having double clinker grinder rolls; and

Fig. 3 is a view similar to Figs. 1 and 2 and showing a preferred embodiment of my invention as applied to a clinker pit having double clinker grinder rolls.

In the operation of grinder roll mechanism associated with combustion apparatus, I have found that agitation of the mass of refuse in a refuse pit by the action of the grinder rolls effects a constant downward sifting of the finer material in the pit and its final escape from the pit ahead of the coarser material with which it is discharged into the pit. The fine material discharged from the combustion apparatus and into the refuse pit is comprised of a relatively high percentage of combustible which, due to the agitation of the larger clinker masses, sifts downwardly and outwardly of the pit before it has time to be consumed, with the result that the combustible content of the ash removed from the stoker represents a very material item of waste. I have found, by analysis, that, with some coals, the combustible content of the ash removed from the refuse pit may be as high as 40%, especially when the stoker is being crowded.

Assuming a coal being burned in the stoker having an ash content of 10%, if the combustible content of the ash is 40%, this would represent a wastage of 4% of the total fuel passing through the furnace.

The wastage above referred to has been very greatly reduced, in accordance with my invention, by the application of a shield beneath the grinder roll or rolls whereby the fine material in the mass of refuse in the pit is prevented from sifting from the pit and it may only be removed by direct action of the grinder roll along with the heavier masses of clinker which are being broken up by the rolls. In this way the finer material, when discharged into the pit together with larger clinker masses, remains associated with the larger clinker masses in the upper part of the pit until it is completely burned. By this means I have found that the percentage of combustible in the ash may be reduced to as low as 5%, which reduction it is apparent, effects a very material saving in the fuel being burned by the stoker.

Referring to the drawings for a better understanding of my invention, I show, in Fig. 1 at 10, a progressive feed stoker which may be of any approved type, and which discharges into a clinker pit 11. The clinker pit 11 is supplied with air for the combustion of the combustible material of the ash from supplementary air boxes 12 and 13 arranged on opposite sides of the pit and discharging through suitable apertures 14 and 16, respectively. Beneath the air boxes 12 and 13, there is suitable structure defining clinker pit front and rear side walls 17 and 18, respectively, while at the bottom of the pit there is arranged a clinker grinder roll 19 carried in suitable bearings 21 and actuated by any suitable means (not shown) so as to rotate in the direction shown by the arrow. The clinker grinder roll in being rotated serves to break up the heavy mass of clinkers and discharges them from the clinker pit all in a manner well understood in the art to which my invention relates.

Heretofore, in the operation of apparatus so far described, the heavier clinker masses being agitated by the clinker grinder roll 19

serve to agitate the whole mass of refuse within the clinker pit and cause a downward sifting of the fine material in the ash and this fine material would sift out of the pit on both sides of the clinker grinder roll due to 5 the agitation, leaving the non-combustible heavy clinker masses in the top of the pit. I have found that this undesired sifting of fine material from the pit may be practically 10 eliminated by the provision of a shield member such as is shown at 22 beneath the clinker grinder roll and secured at 23 to that side of the clinker pit toward which the underside of the roll is moving in rotation. The shield 15 22 should extend the entire length of the clinker pit beneath the roll 19 and it is effective to catch all fine material which would tend to sift downwardly past the roll and cause it to be discharged in a predetermined 20 path of the clinker pit 11 and only by the direct action of the roll 19.

Referring to Fig. 2, I show a clinker pit 26 having a pair of clinker grinder rolls 27 and 28 arranged to be rotated by any suitable mechanism, not shown, in opposite directions as shown by the arrows. With this form of clinker grinder mechanism, there is a tendency for siftings to pass forwardly and rearwardly of the rolls 27 and 28, when the 25 rolls are being operated. I have found that this undesired sifting of fine material may be practically eliminated by the provision of a shield 29 extending transversely across and beneath the rolls 27 and 28 and on which the 30 fine material which first passes the rolls 27 and 28 collects and eventually blocks further sifting thereby.

In Fig. 3, I show a clinker pit 36 having clinker grinder rolls 37 and 38 arranged similar to those shown in Fig. 2. In accordance 40 with the showing of Fig. 3, the undesired siftings from the clinker pit 36 are practically eliminated by the provision of a pair of shields 41 and 42. The shields 41 and 42 are connected respectively, to the rear and front 45 walls 43 and 44 of the clinker pit 36 and they curve inwardly of the pit beneath the rolls 37 and 38, so that a single path is presented for the removal of ash from the clinker 50 pit. The fine material which first sifts past the rolls 37 and 38 is caught on the shields 41 and 42 and further undesired sifting is 55 prevented. Thereafter the fine material discharged into the clinker pit 36 along with the heavier clinker masses is retained in association with such masses until completely burned in the pit, and the ash finally discharged from the pit has a relatively low combustible content.

60 From the foregoing, it will be apparent that I have devised an improved apparatus for preventing the undesired siftings of fine material from the refuse pit of a combustion apparatus while in operation.

65 While I have shown my invention as ap-

plied to a clinker pit which is arranged at the discharge end of a progressive underfeed stoker, it is to be observed that in certain of its broader aspects it is not so limited; for it might equally as well be applied to any refuse pit associated with a combustion apparatus in which it is desired that the sifting of the finer material from the pit be minimized.

While I have shown my invention in but 75 three forms, it will be obvious to those skilled in the art that it is not so limited, but is susceptible of various other changes and modifications without departing from the spirit thereof, and we desire, therefore, that 80 only such limitations shall be placed thereupon as are imposed by the prior art or as are specifically set forth in the appended claims.

What I claim is:—

1. In combustion apparatus, the combination of a pit for receiving the refuse and including an upwardly-extending side wall; a refuse grinding roll arranged within the lower portion of said pit and having its axis disposed in spaced, substantially parallel relation with the side wall of the pit; said grinder roll being provided with projections thereon for grinding the refuse out of said pit, and being supported for rotary motion in a direction to move the refuse away from said side wall; and a shield member forming an extension of said side wall and extending beneath the roll and beyond a vertical plane passing through the axis of said roll to provide a means for minimizing the sifting of relatively fine particles of refuse from between the roll and the side wall of the pit; a substantial part of the lower portions of said shield being arranged in a substantially horizontal plane.

2. In combustion apparatus, the combination of a pit for receiving the refuse and including a pair of spaced, substantially parallel, upwardly-extending side walls; a pair of refuse grinding rolls disposed within the lower portion of said pit and being arranged in spaced, substantially parallel relation to one another; each of said rolls being arranged adjacent to and in spaced, substantially parallel relation with the lower portion of one of the upwardly-extending side walls of the pit; said grinding rolls being provided with projections thereon for grinding the refuse out of the pit, and being supported for rotary motion in directions to move the refuse away from the side walls and to discharge the refuse from between them; and shield members forming extensions of the side walls; each of said shield members having its respective lower outer portion extending beneath its adjacent roll and beyond a vertical plane passing through the axis of said adjacent roll to provide a means for minimizing the sifting of relatively fine

particles of refuse from between each roll and its adjacent side wall of the pit.

3. In combustion apparatus, the combination of a pit for receiving the refuse and including a pair of spaced, substantially parallel, upwardly-extending side walls; a pair of refuse grinding rolls disposed within the lower portion of said pit and being arranged in spaced substantially parallel relation to one another; each of said rolls being arranged adjacent to and in spaced, substantially parallel relation with the lower portion of one of the upwardly-extending side walls of the pit; said grinding rolls being provided with projections thereon for grinding the refuse out of the pit, and being supported for rotary motion in directions to move the refuse away from the side walls and to discharge the refuse from between them; and shield members forming extensions of the side walls; each of said shield members extending beneath its adjacent grinding roll and beyond a vertical plane passing through the axis of said adjacent roll to provide a means for minimizing the sifting of relatively fine particles of refuse from between said adjacent roll and its respective side wall; a substantial part of the lower portion of each of said shields being arranged in substantially horizontal planes.

In testimony whereof, I have hereunto subscribed my name this second day of February, 1927.

ROBERT A. FORESMAN.
